FINGER-OPERATED BOXING TOY

Filed Nov. 29, 1946

UNITED STATES PATENT OFFICE

2,569,260

FINGER-OPERATED BOXING TOY

Harry Schechtel, Los Angeles, Calif.

Application November 29, 1946, Serial No. 712,743

3 Claims. (Cl. 46—142)

1

This invention relates to a toy or amusement device, and has for its principal object the provision of a toy which can be manipulated by the finger of the user to simulate the motions and actions of a boxing bout.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the improved toy;
Fig. 2 is a side view thereof;

Fig. 3 is a cross-section, taken on the line 3—3;
Fig. 2; and

Fig. 4 is a detail section, taken on the line 4—4,
Fig. 3.

The improved toy consists of an ornamental base 10 having two parallel cross frame members 11 and 12 imbedded in or attached to its upper surface. Two human figures 13 and 14 are pivotally mounted between the two members 10 and 12. The figures are cut from suitable sheet material such as heavy cardboard, fiber, plywood or the like and are ornamented to simulate the appearance of a prize fighter or boxer. The figures 13 and 14 are pivoted upon suitable pivot pins 15 mounted in the cross frame members 11 and 12. The pins 15 pass through downwardly extending ears 16 formed on the forward foot of each figure.

Each figure is provided with a pair of freely swinging arms 17 mounted on a shoulder pivot member 18 so that the arms will swing with the movements of the body of the figure to simulate the action of a boxer.

Each of the ears 16 is notched, as shown at 19, in its forward edge below the axes of the pins 15. A leaf spring member 20 of spring steel or the like, extends between the ears from the notch 19 of one block into the notch 19 of the other. The center of gravity of each figure is outside of its pivot pin so that the figure naturally tends to swing outwardly by gravity. The spring member 20, however, limits the outward swing by maintaining the ears 16 resiliently separated.

An operating lever 21 extends across the spring 20. The operating lever is pivoted at the rear of the base 10 upon a suitable pivot pin 22 in a supporting post 23. The forward extremity of the lever terminates in a finger button 24.

2

It can be seen that, if the finger button is depressed, as indicated in broken line in Fig. 3, it will depress the leaf spring 20, causing both the ears 16 to be depressed downwardly at their adjacent edges. This causes both the figures 13 and 14 to swing forwardly, as shown in broken line in Fig. 2, to simulate the movements of a boxer. When the button is released the figures swing back to their original position.

10 As the figures swing forward and back, the arms 17 also swing to create the impression of an actual boxing match.

While a specific form of the improvement has been described and illustrated herein, it is desired 15 to be understood that the same may be varied, within the scope of the appended claims, without departing from the spirit of the invention.

Having thus described the invention, what is claimed and desired secured by Letters Patent is:

20 1. A boxing toy comprising: a base; a pair of parallel frame members extending across said base; a pair of cut-out members representing human figures extending upwardly from between said frame members in face-to-face relation, each figure having one foot ahead of the other; a pivot ear extending downwardly from the forward foot of each figure between said frame members; a pivot pin extending through said frame members and through each of said ears; a substantially rigid connecting member extending between said ears below the plane of said pivot pins; and means for moving said connecting member downwardly to cause said figures to swing toward each other.

35 2. A boxing toy comprising: a base; a pair of parallel frame members extending across said base; a pair of cut-out members representing human figures extending upwardly from between said frame members in face-to-face relation, each figure having one foot ahead of the other; a pivot ear extending downwardly from the forward foot of each figure between said frame members; a pivot pin extending through said frame members and through each of said ears;

40 a leaf spring positioned in notches in and extending between said ears; an operating lever extending transversely across said frame members and resting on said leaf spring; and means for pivoting one extremity of said operating lever

45 to one side of said frame members so that, when the other extremity is moved downwardly, said spring will be moved downwardly to swing said figures toward each other.

50 3. A lever-operated boxing toy comprising: a flat baseboard; two parallel upstanding cross

55

members extending transversally across said base in spaced-apart relation; two flat cut-out figures representing human beings, facing each other with one foot placed ahead of the other positioned over the two parallel cross members; a 5 projection extending downwardly from the forward foot of each figure and between the two cross members, each projection having a notch in its forward edge, the two notches facing each other; pivot pins extending through said cross members and through said projections and pivotally mounting said figures rearwardly of said notches; a straight, resilient member extending from the notch of one projection to the notch of the other projection and serving to hold 10 said projections apart; an operating lever extending across said resilient member at right angles to said cross frame members; and pivot means

supporting one extremity of said lever from said baseboard so that when the other extremity is depressed, said lever will force said resilient member downward to cause the extremities of the latter to act downwardly against said notches to swing the upper portions of said figures inwardly toward each other.
